UNITED STATES PATENT OFFICE.

ONORATO A. AICARDI, OF SAN FRANCISCO, CALIFORNIA.

NEEDLE-THREADER.

SPECIFICATION forming part of Letters Patent No. 707,191, dated August 19, 1902.

Application filed April 14, 1902. Serial No. 102,759. (No model.)

To all whom it may concern:

Be it known that I, ONORATO AGOSTINO AICARDI, a citizen of the United States, residing in the city and county of San Francisco, State of California, have invented an Improvement in Devices for Threading Needles; and I hereby declare the following to be a full, clear, and exact description of the same.

My invention relates to improvements in devices for inserting a thread through the eye of a needle. Its object is to provide a mechanical means whereby either an ordinary sewing-needle or a sewing-machine needle may be threaded with a minimum amount of trouble and loss of time and with the least taxation on the patience and eyesight of the operator.

It consists of a support or stand, a horizontal guide thereon, a threader reciprocable along said guide, a needle-holder in the path of said threader, and means by which the needle is always made to present its eye to said threader and to be engaged thereby.

It also comprises certain means of adjustment, means for severing the thread, and comprises details which will be more fully explained hereinafter, having reference to the accompanying drawings, in which—

Figure 1 is a part longitudinal section and part elevation of my invention. Fig. 2 is a front view of the needle. Fig. 3 is an abnormal section through the holder, showing the operation of threading a needle. Fig. 4 is a plan. Fig. 5 is a plan of the device, illustrating its adaptability for threading a sewing-machine needle, the hand-needle holder being omitted. Fig. 6 is a transverse section on the line $x-x$, Fig. 5.

A represents a portable stand or base of suitable design, upon which is a horizontal bar 2, having a guide-groove 3, in which a carriage or threader 4 is reciprocable.

5 is a needle-holder disposed at the end of the bar 2, having a perforation 6 lying in a vertical plane with the bar and adapted to receive the needle 6^a. This perforation is slightly inclined from the perpendicular for the purpose hereinafter stated. The holder has flanges 7, which are slotted, as at 8, and set-screws 9 fit these slots, whereby a lateral adjustment of the holder on the bar is possible. The under side of the holder has a

transverse notch 9^a crossing the perforation 6, and the holder is adjusted so that this notch lies directly in the path of a barbed projection 10, secured to the threader-block 4. This projection is of such size as easily to pass through the eye of a needle, and its end is adapted to extend beyond the holder and be supported upon a bracket or horn 11. Co-incident with the perforation 6 is a vertical opening in the guide-bar 2, in which a small adjusting-screw 12 is threaded. This screw does not operate, however, above the surface of the bar, for the perforation is contracted into a rectangular shape to form a small recess 13, whose bottom is the end of the screw.

In operation a needle is dropped point uppermost into the holder. The eye end of the needle rests in the recess 13 on top of the screw 12.

By reason of inclining the holder so that the needle stands at an angle to, but in a vertical plane with, the threader-point 10 the needle will always fall into the holder in such a way as to present its eye in line with the barbed-point 10. This is by reason of the fact that the eye always gives two flattened sides to the needle, and the needle will naturally turn on to one of these sides, resting on the end of the screw 12. The screw 12 is adjusted so that the needle is raised or lowered and the bottom of the eye brought even with the plane of the bottom edge of the point 10. The carrier-bar 4 is then reciprocated, so that the threader 10 penetrates the eye and projects beyond to allow a thread to be laid across it. The carrier is then moved in the opposite direction by means of a handle 14, and the tiny barbs on the point 10 sufficiently engage the thread to draw the latter through the eye of the needle. The needle freed from the threader, but threaded with a double strand, may be withdrawn from the holder, the short strand pulled through the eye, and the thread severed by drawing it over the sharp cutter edges 15 of the concaved top of the holder. A spool of thread may be kept always at hand by supporting it on a spindle 16 upon the base. Thus my device may be placed upon a table or anywhere within convenient reach of the operator and is always in readiness. It is possible to thread a needle even in the dark.

- If desired, a holder for needles of different sizes may be placed at either end of the guide-bar 2, in which case the carrier 4 would be provided with a threader-point at each end. 5 However, a single holder will take needles varying several numbers in size. The carriage is retained within the groove by means of a stop-screw 21, projecting up through the bottom of the groove.
- 10 If desired, a form of device may be used by which the holder is adjustable, as in Figs. 5 and 6. In this case the under side of the holder 5' is cut away, as at 9', and two arms or lateral guides 17 are movable toward and 15 from each other to contract or enlarge the space in which the eye part of the needle rests. The guide-bar carries a vertical adjusting-screw 12', by which the depth of the recess 13' is regulated. The lateral adjustment of the guides 17 is effected by means 20 of the right and left threaded screw 18 engaging the plates 19, to which the arms are secured. Springs 20 cause the arms to move in and out equally. The shape of the holder, 25 its inclination, and the operation of the device are precisely as in the first instance.
- In order to adapt the device to thread a needle in a sewing-machine, I have simply provided a holder of suitable form on the 30 other end of the guide-bar 2', employing the same threader-carrier 4', merely arming it with a second barbed threader 10'. This second holder consists in forming a slot-opening 22 through one of the walls of the groove 3' 35 and extending it a little beyond the middle of the bar 2'.
- In operation the bar is moved up or down on the standard A' and set, by means of the lock-screw 23, at a point where the threader 40 10' will be directly opposite the eye of the machine-needle when the latter is at its highest point of travel. The device is then moved to bring the needle 6^b into the guide-slot 22, and by means of a set-screw 24, whose end 45 bears against the needle, the latter is exactly centered in reference to the reciprocating threader 10'. The carrier 4' is prevented from being withdrawn from the groove by means of the pin 25. The walls of the guide- 50 slot 22 are rounded, so as to readily admit the needle, and the projection 11^a furnishes a suitable support for the threader 10' when the latter is projected through the eye of the needle.
- 55 Having once adjusted the device to any size of needle or style of machine, it can remain set in that position and used indefinitely.
- In order to hold the thread 26 stretched 60 across the horn in the path of the threader and allow the operator's hands to be free, I may provide a light wire loop or holder 27. It must engage the thread, however, but slightly, so as not to prevent its being readily drawn through the eye by the retracting threader.

Having thus described my invention, what I claim, and desire to secure by Letters Patent, is—

1. In a device of the character described, 70 the combination of a stand, a horizontal guide-bar provided with a socket for the eye end of the needle, a carrier reciprocable on said guide-bar, a barbed threader-point on said carrier and means in connection with said bar by 75 which a needle may be held at an angle to, but in a vertical plane with, the threader-point, to automatically present its eye to said threader.
2. In a threading device, the combination 80 of a horizontal guide-bar provided with a socket for the eye end of the needle, a carrier reciprocable on said guide-bar, a barbed threader on said carrier, a needle-holder disposed in the path of said threader, said holder 85 arranged at an angle to, but in a vertical plane with, the threader-point, for centering the needle.
3. The combination in a threading device, 90 of a guide-bar, a carrier slidable thereon, a threader-point on said carrier, a guide means for holding a needle in the path of said threader and means for lateral adjustment of said needle-holder.
4. In a threading device, the combination 95 of a guide-bar, a carrier slidable thereon, a barbed threader-point on said carrier, a needle-holder on said bar, and means by which the eye of the needle will automatically position itself in the holder and always present 100 itself in the path of the threader.
5. The combination in a threading device, 105 of a guide-bar, a carrier slidable thereon, a threader-point on said carrier, a needle-holder, said needle-holder having a perforation adapted to receive the needle and means by which the needle may be raised or lowered to bring the eye of the needle into the path of the threader.
6. The combination in a threading device 110 of a guide-bar, a carrier slidable thereon, a threader-point on said carrier, a needle-holder disposed in the path of said carrier and having a transverse adjustment on said guide-bar, means by which the vertical adjustment 115 of the needle is effected, and means by which the needle is made to turn automatically to present its eye in the path of said threader-point.
7. The combination in a threading device, 120 of a guide-bar provided with an adjustable socket to receive the eye end of the needle, a carrier slidable on said guide-bar, a threader-point on said carrier and a needle-holder adapted to hold a needle at an incline in relation to the line of movement of said threader 125 but in the same vertical plane therewith.
8. The combination in a threading device, 130 of a guide-bar, a threader reciprocable thereon, a needle-holder disposed in the path of said threader, said holder having an inclined perforation adapted to receive and hold the

needle whereby the needle is made always to present its eye to the threader and cutting means upon the holder for severing the thread.

9. The combination in a threading device, 5 of a support, a horizontal guide-bar vertically adjustable thereon, a reciprocable threader on said bar, a needle-holder, lateral and vertical adjusting mechanism whereby a needle is centered in said holder in relation to the

threader and a spool-holding means on said support.

In witness whereof I have hereunto set my hand.
